COSMETIC DISPENSER

Willie Mae Sutton Miller, Chicago, Ill.

Application July 21, 1955, Serial No. 523,503

1 Claim. (Cl. 132—83)

My invention relates to containers and particularly to containers for cosmetics and cosmetic implements.

One purpose is to provide a container for a plurality of individual cosmetic containers and having means for removably securing certain cosmetic implements therein.

Another purpose is to provide a container having a particular formation facilitating its use in the hand of the user.

Other purposes will appear from time to time in the course of the specification and claim.

I illustrate my invention more or less diagrammatically in the accompanying drawings wherein:

Figure 1 is a top view, with parts broken away.

Figure 2 is a side view in partial cross-section, on the line 2—2 of Figure 1.

Figure 3 is a perspective view of a variant form of my invention.

Figure 4 is a top view with parts broken away of the device illustrated in Figure 3.

Figure 5 is an end view in cross-section on the line 5—5 of Figure 4.

Like parts are indicated by like symbols throughout the specification and drawings.

Referring now to the drawings and particularly to Figures 1 and 2, the numeral 1 generally indicates the lower portion of my device which comprises a generally box-like structure having a bottom wall 2, a curved side wall 3 and is generally upwardly open. A hinge 4 may be positioned along the upper edge of a somewhat straight rear portion 5 of the side wall 3. A cover 6 may be hingedly secured to the side wall portion 5 for rotation toward a rear position such as that illustrated in dotted lines in Figure 2.

The side wall 3 may have oppositely curved portions 10, 11, diverging from opposite edges of the straight portion 5 and hinge 4. Curved portions 12, 13 of the side wall 3 may converge inwardly from the outer ends of the curved portions 10, 11 and may join an outwardly offset generally rounded projection 15 of the side wall 3 as indicated at the reversed curved portions 17, 18 of the side wall 3. A clip member 20 may be connected to the side wall 3 at the outermost portion of the projection 15 and may cooperate with a securing member 21 on the cover 6 to retain the cover in normally closed position.

A mirror 25 may be connected to the inner or under surface of the cover 6 as indicated clearly in Figure 2 and may have its reflecting surface directed outwardly from the cover 6 to be visible to the user when the cover 6 is in the dotted line position illustrated in Figure 2.

A cosmetic and implement receiving structure may fit within and be secured within the curved wall 3 and may rest upon the bottom wall 2 of the container portion 1. This receiving structure may comprise a supporting edge wall 30 and may have a plurality of upwardly open well portions 31 spaced along the side wall portions 10, 5 and 11 as best seen in Figure 1. The wells 31 may, for example, be circular in lateral cross-section. A gen-

2

erally rectangular, centrally located well 32 may be positioned between two of the wells 31, as illustrated in Figure 1, and may have secured to the bottom thereof a plurality of upwardly open implement-receiving and holding clip members 33, 34, 35. I illustrate, for example, a cosmetic pencil 33a held between a pair of clip members 33, a cosmetic brush 34a held between a pair of clip members 34, and a third cosmetic implement 35a held by a pair of clip members 35. Positioned within the generally rounded projection 15 is a well 40 which may be provided, for example, to contain face powder. As illustrated in Figures 1 and 2, the well 40 may be generally circular and may follow the outline of the rounded projection 15. A cover 41 is provided for the well 40 and is hingedly secured thereto as indicated generally at 42.

It will be understood that the wells 31 may have downwardly inserted therein containers for cosmetics. I illustrate for example, five such wells 31, each of which may have positioned therein individual containers for a different cosmetic material. Similarly, the well 32 may contain a variety of cosmetic implements to suit the desires of the user. While the well 40 is described as preferably containing face powder, it will be understood that various cosmetics may be contained therein without departing from the nature and scope of my invention.

Referring now to Figures 3—5, I illustrate a variant form of my invention. Referring particularly to Figure 3, the numeral 50 generally indicates a triple-section container for cosmetics and cosmetic implements comprising a lower base portion 51, a central container portion 52 and an upper cover portion 53. The cover 53 may have secured to the inner surface thereof a mirror 54 having its reflecting surface directed downwardly or outwardly from the cover 53 so as to be visible to the user when the cover 53 is in raised position.

As best seen in Figure 5, the cover 53 is hingedly secured along a rear edge of the central section 52 as indicated at 55 and the central section 52 is hingedly secured along an upper rear edge of the base section 51 as indicated generally at 56. It will be understood that the central section 52 has a bottom wall 60 and four side walls generally indicated by numeral 61. Exposed within the central section 52 and covering a portion of the bottom wall 60 thereof, is a support 63 which carries a plurality of divider walls generally indicated by the numeral 64. As indicated best in Figure 4, the divider walls 64 serve to create separate upwardly open wells covering approximately half of the central section 52. The walls 65 thus created may have placed therein a plurality of smaller containers having a variety of cosmetic materials therein. The remaining portion of the central section 52, as illustrated in the drawings, the forward portion, may be suitably divided. I show for example one longitudinally extending divider 70, into separate compartments to receive a plurality of individual cosmetic materials. The well 71 created by the divider 70 and the forward portion of the support 63 and dividers 64 may have clip means 72 therein into which a toothbrush 73, for example, may be inserted and held. A forward wall 75 of the central section 52 may have a plurality of clip means 76, 77 into which a variety of implements 78, 79 may be inserted and held for easy removal.

The lower or base section 51 may similarly have dividers, such as the divider 80 illustrated in Figure 3, to segmentalize the upwardly open base section 51 within its bottom wall 81 and four side walls indicated generally by the numeral 82.

A second mirror 85 may be secured to the lower or bottom wall 60 of the central section 52 so as to be visible to the user when the section 52 is raised into upright position. A clip means 90 may be secured to the

top 53 and central section 52 to hold the top 53 in normally closed position on and against the central section 52 and a clip means 91 may similarly be secured to a lower portion of the central section 52 and the base section 51 to hold the central section 52 in normally closed position against the base 51. Thus the user may choose to separate the clasp 90 and raise the cover 53 using the mirror secured thereto and the cosmetics and implements from the central section 52. In the alternative, the user may choose to separate the clasp 91 and raise the central section 52 and the cover 53 together, utilizing the mirror 85 which is thus brought into view and materials from the base section 51.

It will be understood that the wells 65, 71 and 75, as above described, may be suitably formed in the base section 51 without departing from the nature and scope of my invention. Similarly, the device of Figures 3-5 may be of a size useable on a dressing table or may be made small enough to be carried in a lady's purse.

It will be realized that, whereas, we have described and illustrated a practical and operative device, nevertheless many changes may be made in the size, shape, number and disposition of parts without departing from the spirit of our invention. We therefore wish our description and drawings to be taken as in a broad sense illustrative or diagrammatic, rather than as limiting us to our precise showing.

The use and operation of my invention are as follows: The device illustrated in Figures 1 and 2 may be easily held within the hand of the user, the projection 15 being directed along the palm or base of the hand, the fingers being free to grasp the generally oval-shaped remainder of the container, the curved sections 10, 11, 12 and 13 being easily held between the fingers. With the cover raised as shown in dotted lines in Figure 2, the user may select the appropriate implement from the well 32 and may employ cosmetics from any of the wells 31 or the well 40 as she desires. The user is thus provided with what is, in effect, an artist's palette which she may use, much in the manner of artists, in applying cosmetics.

Referring to the variant form of my invention, as illustrated in Figures 3-5, I provide a type of combination of vanity and cosmetic case which the user may, for example, use either at home or at almost any time, depending upon the size of the container. Since the container illustrated in Figures 3-5 is in effect in three sections, a greater amount of materials and items may be contained therein. The user may, for example, place a plurality of containers of varying cosmetics in the wells

65 and a variety of implements in the wells 71, 75, the lower or base section 51 may contain supplementary items, including, for example, tissues and additional instruments. Materials described as being in central section 52 and base section 51 may, of course, be reversed without departing from the nature and scope of my invention. Since a mirror is provided against the under surface of the cover 53 and a second mirror is provided against the under surface of the central section 52, it is clear that the user may utilize cosmetics, implements or other materials from either the central section 52 or the base section 51 without having to open both clasps 90, 91.

I claim:

15 In a cosmetic container, an upwardly open case having a substantially flat bottom wall, a cover for said case hingedly mounted thereon along the rear edge thereof and having a substantially flat top wall, said case and cover having a generally elliptical periphery and an outwardly-directed projection positioned generally centrally of the forward edge thereof and in general alignment with said hinged mounting, the outer portion of said projection having a generally circular edge, said outer portion being joined with said forward edge of said case and cover by oppositely curved portions extending laterally in opposite directions from said outer portion, said case having a support positioned entirely therewithin, said support extending throughout said case and of substantially the configuration thereof, said support having a plurality of individual wells spaced along said hinge and along the rear curved edge of said elliptical central portion adapted to receive a plurality of individual cosmetic materials, said support having a larger well positioned within the area of said projection and a central well in said support positioned between said wells along said hinge and said well in said projection, said central well having secured to the bottom wall thereof a plurality of upwardly open securing means adapted to receive and hold a plurality of cosmetic instruments.
